UNITED STATES PATENT OFFICE.

WILLIAM WESLEY SELVIDGE, OF LOCKESBURG, ARKANSAS.

PLOW.

SPECIFICATION forming part of Letters Patent No. 371,220, dated October 11, 1887.

Application filed July 5, 1887. Serial No. 243,392. (No model.)

To all whom it may concern:

Be it known that I, WILLIAM WESLEY SELVIDGE, a citizen of the United States, residing at Lockesburg, in the county of Sevier and State 5 of Arkansas, have invented certain new and useful Improvements in Plows; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention is an adjustable double-shovel plow; and it consists in the novel construction and arrangement of its parts.

In the accompanying drawings, Figure 1 is an elevation of my plow. Fig. 2 is a top plan view of the same. Figs. 3, 4, and 5 are detail views.

My invention is described as follows:

The beam A consists of two pieces, *b b*, the front ends of which are bolted, one on either side of the draft-hook *b'*, their rear ends being 25 wide enough apart to straddle a row of corn or cotton, and are adjustable by means of the right-and-left-threaded rod C, which extends through the rear ends of the same. This adjusting-rod C has on either end two adjusting-nuts, *c c'*, which work against the inner and outer faces of the side beams. Said rod C has also rigidly secured to it a hand-lever rod, *c''*, by which the rear ends of said beam *b* may be 30 adjusted with the hand without the necessity of using a wrench to turn the said nuts. These beams *b* are of sufficient depth to make them stout; but are quite thin, and will spring sufficiently to meet the requirement of the adjusting-rod C. Their rear ends curve down a 35 little and then terminate, and to them are hinged the curved slotted plow-standards D. To the feet of these curved slotted plow-standards are secured plow-points E, by means of the T-shaped clamp *e*, the upper end of which 40 rests against the upper end of the said plow-point. Its shank passes through the slot *d* in the said standard, and its washer end rests

against the rear edge of said standard, the whole being secured by a bolt and nut. The shank, however, may be attached to one end 50 of the head and may pass on the outside of the said plow-standard. These plow-standards are adjustable in relation to their angles—that is to say, both of them may be set forward or back, or either one may be set forward and the other back. This is accomplished by means of the rods *d*, clamps *d'*, and thumb set-screws *d''*. The lower ends of the rods *d* are hinged in the slots of the plow-standards. Their front ends terminate in star-shaped teeth *f*, and are 60 pivoted in the lower ends of the clamps *d'*, the teeth being adapted to catch in the notches *f'*, which are made in the lower edges of the beams *b*. The thumb set-screws work in the upper 65 ends of said clamps, and are adapted to catch in the notches *f''* in the upper edge of said beams.

The operation of this device is apparent. The handles of the said plow are secured to the beams in the ordinary way and made adjustable by perforated supports.

Having thus described my invention, what I claim as new, and desire to secure by Letters Patent, is—

In an adjustable double-shovel plow, the 75 combination of the beams *b b*, secured to the draft-hook *b'*, and having the notches *f' f''* in their upper and lower edges, curved slotted plow-standards D, pivoted to the rear ends of said beams, rods *d*, their rear ends pivoted to 80 the said standards, their front ends terminating in the star-shaped teeth *f*, and pivoted in the lower ends of the clamps *d'*, clamps *d'*, working on the beams *b*, thumb set-screws *d''*, working in the upper ends of said clamps and 85 in the notches *f''* of said beams, substantially as shown and described, and for the purposes set forth.

In testimony whereof I affix my signature in presence of two witnesses.

WILLIAM WESLEY SELVIDGE.

Witnesses:

WILLIAM K. PERKINS,
ARCHELAUS C. STEEL.
